MOISTENER

William Howard Johnson and Lester Howard Johnson, Santa Barbara, Calif., assignors of one-third to Jasper M. Lane, North Long Beach, Calif.

Application August 3, 1939, Serial No. 288,222

1 Claim. (Cl. 91—54.4)

This invention relates to an envelope moistener, the general object of the invention being to provide a container for water having slots in its top with a wick passing through the slots with its ends in the water and a portion of the wick extending over the top.

The invention also consists in certain other features of construction, combination and arrangement of the several parts, to be herein-after fully described, illustrated in the accompanying drawing and specifically pointed out in the appended claim.

In describing the invention in detail reference will be had to the accompanying drawing wherein like characters denote like or corresponding parts throughout the several views, and in which:

Figure 1 is a perspective view of a moistener as constructed in accordance with this invention.

Figure 2 is a sectional view thereof approximately on line 2—2 of Figure 1.

Figure 3 is a sectional view similar to Figure 2 showing a modified form of the moistener.

As shown in this drawing the device includes a container 1 for the liquid, the container being closed by a removable cover 2 having a pair of slots 3 therein. A wick 4 passes through these slots into the liquid with a portion of the wick extending over the top of the cover between the slots. Thus the liquid is drawn to the top part of the wick by capillary attraction and this damp portion of the wick at the top of the cover will moisten the envelope.

In the modification the container 1' is formed with an integral cover and the slots 3' are formed therein for the wick. In order to permit water to be placed in the container the cover is provided with a hole 5 between the slots and which is normally covered by the wick. By lifting the wick the hole is exposed so that liquid can be poured through the same into the container. If desired the hole can be closed by a

stopper. It is to be observed that in both of the forms the upper side of the box is in the shape of a segment of a cylinder and is upwardly convex. The reason of this peculiar formation is that one is enabled to wipe the edge of an envelope flap over the pad 4 without the gummed part coming in contact with the top wall or lid. Thus the top wall or lid is at all times kept clean and free from gummy deposits. At the same time this curvature of the top wall presents a saddle like surface for the moistening strip so that a good contact between the envelope and the moistening strip may be obtained by bending the ends of the envelope slightly downward. This makes it unnecessary to force the envelope into contact with the moistening pad by pressure with the fingers on that part of the envelope in contact with the pad and the danger of soiling the fingers is thus eliminated.

It is thought from the foregoing description that the advantages and novel features of the invention will be readily apparent.

It is to be understood that changes may be made in the construction, combination and arrangement of the several parts, provided such changes fall within the scope of the appended claim.

What I claim and desire to protect by Letters Patent is:

An envelope moistener comprising a rectangular receptacle, an overhanging cover having an arcuate upper surface coinciding with a curved plane whose axis is remote from the bottom of the receptacle, said cover having laterally extending slots therein and a wick of lesser width than the cover disposed on the arcuate surface thereof and extending through the slots with its extremities extending in close relation to the bottom of the receptacle.

WILLIAM HOWARD JOHNSON,
LESTER HOWARD JOHNSON.
